(57) **CLAIM**

The ornamental design for a handheld computer terminal device as shown and described.

DESCRIPTION

FIG. 1 is a front perspective view of the handheld computer terminal device according to my design.

FIG. 2 is a back perspective view thereof.

FIG. 3 is a front elevation view thereof.

FIG. 4 is a back elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an exploded partial perspective view of an isolated portion of FIG. 1.

The broken lines in FIGS. 1-9 represent portions of the handheld computer terminal device and form no part of the claimed design.

1 Claim, 9 Drawing Sheets
